United States Patent Office

Des. 185,571

Patented June 23, 1959

185,571

TOY MECHANICAL HAND

Bayard C. Reed and Carl Ayala, Chicago, Ill., assignors
to Marvin I. Glass, Chicago, Ill.

Application March 7, 1958, Serial No. 49,953

Term of patent 3½ years

(Cl. D34—15)

Figure 1 is a perspective view of a toy mechanical hand showing our new design;

Figure 2 is a side elevational view;

Figure 3 is a plan view; and

Figure 4 is a front elevational view thereof.

We claim:

The ornamental design for a toy mechanical hand, substantially as shown.
